UNITED STATES PATENT OFFICE.

WILLIAM STEVENSON, OF CHICAGO, ILLINOIS.

BRAKE-BEAM.

No. 823,306.

Specification of Letters Patent.

Patented Jan. 1, 1906.

Application filed March 12, 1906. Serial No. 305,558.

To all whom it may concern:

Be it known that I, WILLIAM STEVENSON, a citizen of the United States, and a resident of Chicago, Cook county, Illinois, have invented a certain new, useful, and Improved Brake-Beam, of which the following is a full, clear, and exact specification, such as will enable others skilled in the art to which it pertains to make and use the same.

10 My invention relates to improvements in brake-beams, and has special reference to improvements in brake-beams of that class which are known as "single-member" beams, such a brake-beam having as its principal member a rolled flanged beam of structural shape, usually an I-beam.

The object of my invention is to provide a brake-beam which shall be of minimum weight and of maximum strength.

20 Another object of the invention is to provide a brake-beam at less cost than any other brake-beams of its class.

With these objects in view my invention consists generally in a brake-beam comprising a rolled flanged beam of greatest depth at the middle in combination with a suitable fulcrum piece or pieces, preferably constituting a reinforcement or strut for the middle of the beam.

30 My invention also consists in particular forms and constructions and in combinations of parts, all as hereinafter described, and pointed out in the appended claims.

My invention will be more readily understood by reference to the accompanying drawings, forming part of this specification, and in which—

Figure 1 is a top view of a brake-beam embodying my invention. Fig. 2 is a top view 40 of the main element or member of my improved brake-beam, slightly modified. Fig. 3 is an enlarged cross-section thereof on the line $x-x$ of Fig. 1. Fig. 4 illustrates a modification of the structure in which a single bolt 45 is employed for securing the fulcrum-pieces. Fig. 5 is a view showing the beam with a modified middle cross-section. Fig. 6 is an enlarged cross-section or end view of the beam, standing also for the cross-section of 50 the original beam before it is spread, as hereinafter described.

The purpose of this invention is to improve what is known as the "single-beam" type of brake-beam. Brake-beams of this class 55 which are now on the market are made from five-inch and from six-inch I-beams of stand-

ard cross-sections. It is well known that the five-inch brake-beams which are now in use do not comply with the requirements of the Master Car-Builders' Association, forasmuch as they are deficient in strength. It is for 60 this reason that the six-inch beam was resorted to. The objection to the six-inch beam is that its width is too great to admit it in the space which is allowed in the car-truck. 65 This is also true of the five-inch beam, and out of this fact has grown a custom of compressing the ends of both five and six inch beams to a dimension of about four inches. The ordinary truck will not accommodate a 70 larger beam when the brake-heads and brake-shoes are applied thereto. The manifest and well-known advantages of a single beam, and particularly the low cost of such brake-beams, has led to the use of large numbers 75 thereof notwithstanding the fact that they are comparatively inefficient and unreliable. The beams which are compressed or reduced in "height" at the ends suffer from this distortion, being thereby further weakened, and 80 it is also well known that the process of compressing the ends is slow and expensive. Furthermore, the compressed end of such a beam offers a poor seat for the brake-shoe head, which must needs be attached thereto. 85

The special object of my invention is to provide a brake-beam which shall be free from the faults, weaknesses, and other objectionable features of the single-beam devices in present use and to provide a beam 90 which shall be of even less weight than the ordinary beam and yet stronger and which shall have ends that are admirably fitted to receive the brake-shoe heads. I accomplish these ends by making and employing a 95 rolled flanged beam of a new cross-section, the characteristic of which is that its flange width is equal to or is greater than the beam's height. When the beam is in use, its web occupies a horizontal plane; but in describing 100 the same I shall employ ordinary terms, referring to the distance between the edges of the flanges as the "width" of the beams and terming the distance across the web as the "height" of the beam. 105

My invention may be carried out with a rolled flanged beam of channel shape in cross-section; but I much prefer a beam of I shape in cross-section. In either case the width of the beam equals or exceeds the height of the 110 beam.

Practically speaking, the height of the

beam is determined by the space that is available in the truck to which the brake-beam is to be applied, taken in connection with the pull or load which is to be imposed upon the beam, and from the foregoing it will be obvious that the width of the beam is determined by its height. The wide flanges of the beam are amply sufficient to withstand all transverse stresses, but being of small height, usually not exceeding four inches, would not be strong enough to sustain the direct pull of the brake mechanism on the beam. To overcome this difficulty and to secure the necessary strength at the center of the beam, I separate or force apart the two flanges until they occupy the requisite relation to the neutral axis of the beam. The flanges are then braced by a strut, the beam taking the form of a fish-belly beam of theoretical shape proportioned to the same loads. The ends of the beam are not distorted in any way, and therefore provide the best possible seats for the brake-shoe heads.

Referring now to the drawings, and particularly to Fig. 6, it will be seen that I employ a beam whose web 2 is of no greater, and usually of less, width than the flanges 3 3. Fig. 6 represents the cross-section of the original beam and also represents the cross-sections of the ends of the completed brake-beam. The middle of the beam is of greater height, the flanges 3 3 being separated at that point, as shown by the other figures of the drawings. For illustration, in cases where the ends of the beam are four inches in height I make the middle of the beam at least six inches in height. When the separated flanges are joined by a strut, such beam becomes quite as strong, in fact stronger, than the usual six-inch I-beam. It weighs much less, costs less, and is stronger than the usual beam, and herein lies the special advantage of my invention.

By applying sufficient force the middle or central portion of the web of the beam may be distended (see Fig. 1) without rupturing the web by thinning the same, as shown at 2^a in Fig. 5. The pulling or spreading of the flanges may be facilitated by splitting the web of the beam, as shown in Fig. 2, and this is the preferred way of making the member. I prefer that the compression-flange—i. e., the flange opposite the brake-heads—shall be straight, as shown in the drawings; but it is obvious that both flanges of my beam may be distended, if desired, and it is also obvious that the degree of distension—in other words, the distance between the flanges at the center of the beam—determines the load-carrying strength thereof.

I may provide my beam with a strut or struts independent of the fulcrum-piece; but as the fulcrum-piece requires a fastening upon the beam I prefer to make the struts and the fulcrum-piece integral. Thus the angularly-

positioned fulcrum piece or jaw 6 is preferably formed in two parts, the member 6' of which embraces the flanges and the web of the beam. These portions are secured together and to the beam by one or more rivets 7⁰ 6" and constitute an effective strut. If desired, a single rivet 6" may be used, as shown in Fig. 4. Such construction avoids the piercing of the web portions; but in most cases I provide each of the web parts 2' with a rivet-hole to receive the rivets 6". The strut serves to hold the flanges 3 3 in fixed position at the center, and at the ends the flanges are joined by the solid portions of the web 2. The brake-heads 5 may be of any desired pattern or form and are made to closely fit the ends of the tension-flange of the beam and also the web of the beam. They are secured upon the beam by means of rivets or bolts 5'. In manufacturing 8⁰ these beams I prefer that one flange shall be held in a stationary die and that the other shall be grasped in a movable die or clamp, the latter being drawn or pulled away from the stationary die until the beam is given the necessary web height. As stated, the operation is simplified by previously splitting the web, as indicated in Fig. 2. The torturing or rupturing of the metal at the ends of the beams may be wholly averted by subjecting 9⁵ the beam to endwise pressure during the operation of the dies. The manner of treating a channel-beam is the same as described in connection with an I-beam.

As various modifications of my brake-beam as herein shown and described will readily suggest themselves to others, I do not confine my invention to these specific constructions.

Having thus described my invention, I claim as new and desire to secure by Letters Patent—

1. A brake-beam of the single-beam type comprising a single, rolled, flanged beam of a width at least equaling its height and having its flanges forced apart at the middle, in combination with a suitable strut, fulcrum-piece and heads, substantially as described.

2. A brake-beam of the single-beam type comprising a single, rolled, flanged beam of a width at least equaling its "height," the web of said beam being split and the flanges thereof being forced apart at the middle, in combination with a suitable strut, a fulcrum and heads, substantially as described.

3. A brake-beam comprising a single, rolled, flanged beam of a width at least equaling its "height," in combination with a fulcrum-piece and brake-heads, the flanges of said beam being forced apart at the middle of the beam to afford requisite strength in the plane of the web of the beam, substantially as described.

4. A brake-beam comprising a single 13⁰

rolled, **I**-beam, having flanges whose width at least equals the "height" of the beam and whose web is distended at the middle, in combination with a suitable strut and brake-heads, substantially as described.

5. A brake-beam comprising a single, rolled, **I**-beam, having its web split and its flanges distended at the middle, the width of said flanges being at least equal to the height of the web at the ends of the beam, in combination with a suitable strut, a fulcrum and brake-heads, substantially as described.

6. A brake-beam comprising a single, rolled, **I**-beam, of a width at least equaling

its "height" and having its web distended at 15 the middle, whereby the flanges are abnormally separated at that point, in combination with a fulcrum-piece, corrected portions forming a strut between the flanges of the beam and brake-heads attached to the ends 20 of said beam, substantially as described.

In testimony whereof I have hereunto set my hand, this 8th day of March, 1906, in the presence of two subscribing witnesses.

WILLIAM STEVENSON.
